US00D703051S

(12) **United States Design Patent**
Riley et al.

(10) **Patent No.:** **US D703,051 S**
(45) **Date of Patent:** **** Apr. 22, 2014**

(54) **CONTAINER**

(71) Applicants: **Lauren Ashley Riley**, Cincinnati, OH (US); **Brett Taylor Read**, Cincinnati, OH (US); **Douglas Michael McGahan**, Cincinnati, OH (US); **Barry Robert Prather**, Cincinnati, OH (US)

(72) Inventors: **Lauren Ashley Riley**, Cincinnati, OH (US); **Brett Taylor Read**, Cincinnati, OH (US); **Douglas Michael McGahan**, Cincinnati, OH (US); **Barry Robert Prather**, Cincinnati, OH (US)

(73) Assignee: **The Procter & Gamble Company**, Cincinnati, OH (US)

(**) Term: **14 Years**

(21) Appl. No.: **29/440,283**

(22) Filed: **Dec. 20, 2012**

(51) LOC (10) Cl. **09-01**

(52) U.S. Cl.
USPC **D9/503**; D9/441; D9/454; D9/539; D9/558

(57) **CLAIM**

The ornamental design for a container, as shown and described.

DESCRIPTION

FIG. 1 is a top, front perspective view of a container showing our new design;

FIG. 2 is a top, rear perspective view of the container of FIG. 1;

FIG. 3 is a front view of the container of FIG. 1;

FIG. 4 is a side view of the container of FIG. 1;

FIG. 5 is a rear view of the container of FIG. 1;

FIG. 6 is a side view of the container of FIG. 1, opposite the side view shown in FIG. 4;

FIG. 7 is a top view of the container of FIG. 1; and,

FIG. 8 is a bottom view of the container of FIG. 1.

The broken lines in the drawings illustrate the portions of the design that form no part of the claim.

1 Claim, 4 Drawing Sheets
